UNITED STATES PATENT OFFICE.

PATRICK H. DONOVAN, OF PITTSBURGH, PENNSYLVANIA, ASSIGNOR TO THE WESTINGHOUSE AIR BRAKE COMPANY, OF WILMERDING, PENNSYLVANIA, A CORPORATION OF PENNSYLVANIA.

DRAW-BAR-SLACK ADJUSTER.

1,307,087.

Specification of Letters Patent. Patented June 17, 1919.

Application filed November 8, 1916. Serial No. 130,159.

To all whom it may concern:

Be it known that I, PATRICK H. DONOVAN, a citizen of the United States, residing at Pittsburgh, in the county of Allegheny and 5 State of Pennsylvania, have invented new and useful Improvements in Draw-Bar-Slack Adjusters, of which the following is a specification.

This invention relates to apparatus for 10 stopping trains, and more particularly in connection with the use of brakes on long trains.

With the usual brakes employed for stopping trains, such as the well known fluid 15 pressure brake, a certain amount of time is required to transmit the braking action from the point of initiation at the head end of the train to the rear end and as a consequence, the brakes are applied at the front 20 end of the train before any braking action takes place at the rear end.

There is always a certain amount of slack 25 in the draw-bar and coupler at each car and this permits the unbraked cars at the rear end of the train to "run in" on the braked cars at the head end of the train, thus causing damaging shocks particularly on long trains.

While it is necessary to have some slack 30 in the train to enable the train to be started, as well known, slack is only a detriment to the handling of the train in stopping.

According to the principal feature of my 35 invention it is therefore proposed to provide means for taking up the slack when an application of the brakes is to be made, so that the train being substantially rigid, the train can be stopped as a unit, to a large extent, regardless of the fact that the brakes are 40 applied at one part of the train before they are applied at another part.

In the accompanying drawings; Figure 1 is a diagrammatic view of a car brake and draw-bar equipment embodying my invention; 45 Fig. 2 a similar diagrammatic view, showing a modified form of my invention; Fig. 3 an elevational view of an apparatus embodying my invention, which is adapted to be controlled manually; Fig. 4 a plan view of still another form of my invention; 50 and Fig. 5 an elevational view thereof.

According to the construction shown in Fig. 1 of the drawings, 1 indicates a fluid

pressure brake apparatus connected to the usual brake rigging 2. The usual car coupler 3 is connected by a draw-bar 4 with a draft gear 5 and according to one form of my invention there is interposed between the end sill 6 of the car and the coupler 3 a pair of wedge blocks 7, adapted when forced inwardly to take up the slack between the coupler and the end sill.

The wedge blocks 7 may be operated through levers 8, pivoted to the sill 6 and connected to toggle links 9. The toggle links 65 9 are connected together by a link 10 which is operatively connected to a rod 11 having a pivoted connection with the brake rigging 2.

Springs 12, applied to the end sill 6 and 70 acting on levers 8 may be employed to assist in the release movement of the parts and a spring 13, may be interposed in the rod 11 to provide elasticity and prevent undue strain on the parts.

In operation, the parts being in release, as 75 shown in Fig. 1, upon applying the brakes, the movement of the brake rigging exerts a pull on the rod 11 which tends to straighten the toggle links 9 and thereby force the 80 wedge blocks together, so as to take up any slack which may exist between the coupler 3 and the end sill 6.

Since the slack is thus taken up when the 85 brakes are applied, the slack cannot run in by reason of the fact that the brakes are applied at the head end of the train before they are applied at the rear end and consequently 90 damaging shocks are prevented.

In releasing, the toggle links 9 return to 95 release position and the wedge blocks 7, assisted by the springs 12, will be moved outwardly, so that the usual slack will exist while the train is running and can be utilized to assist in starting the train, as herefore.

Instead of operating the slack take-up device through the movement of the brake rigging, a separate operating cylinder may be employed, such as the cylinder 14, shown in 100 Fig. 2 of the drawings.

The piston rod 15 of said cylinder may be connected to a floating lever 16 having a pivoted connection with the rods 11 extending to the slack take-up devices at opposite ends of the car.

In operation of the construction shown in Fig. 2, when the brakes are applied, fluid under pressure supplied to the usual brake cylinder is also supplied through pipe 17 to the cylinder 14 and the piston rod 15 is thereby operated to exert a pull on the rods 11, so that the wedge blocks 7 are actuated as in the case of the Fig. 1 construction.

According to another form of my invention, as shown in Fig. 3 of the drawings, the slack may be taken up manually before the train is started, by providing pivoted levers 18 for operating the wedge blocks 7. The other ends of the levers 18 are connected to chains 19 having a common connecting link 20 to which is connected a chain 21 adapted to be wound on a drum 22 carried by a horizontally arranged shaft 23.

At opposite ends of the shaft 23 are secured hand wheels 24 and ratchet wheels 25 may be provided on said shaft having engaging pawls 26 for locking the shaft 23 in its adjusted position. A hand operated shaft 27 may be provided for lifting the pawls 26 when it is desired to release the wedge blocks 7.

In operation, before the train is started, one of the hand wheels 24 is operated to rotate the shaft 27 and wind up chain 21, so as to effect the closing in of the levers 18 and the inward movement of the wedge blocks 7, sufficient slack being left to insure the ready starting of the train. If it is desired to release the wedge blocks 7, the shaft 27 is operated to lift the ratchet pawls 26 and thus permit the release movement of the parts, assisted by the release springs 12.

In Figs. 4 and 5 of the drawings, is shown another construction, in which the slack is taken up by providing teeth 28 on a push rod 32 mounted below the draw-bar and a pawl 29 adapted to be actuated by means of a bell crank 30 connected to the rod 11.

A downwardly extending lug 33 is pro-

vided on the coupler head 3 and a spring 34 acts on the push rod 32 and tends to maintain same in engagement with the lug 33.

In operation, when the train is running, the stretch or slack is followed up by the push rod 32 maintaining engagement with the coupler lug 33 through the action of spring 34 and upon applying the brakes, the bell crank 30 being fulcrumed at 31, the pull exerted on the rod 11 when the brakes are applied, as hereinbefore described, causes the bell crank to throw the pawl 29 into engagement with one of the teeth 28 and thus lock the push rod 32, so that the coupler head is held out and the train slack is prevented from running in.

Having now described my invention, what I claim as new and desire to secure by Letters Patent is:

1. The combination with a draw-bar and means for applying the brakes, of mechanism operatively connected to said means and operating upon applying the brakes to take up draw-bar slack.

2. The combination with a car coupler and the end sill of a car, of wedge blocks and means operated upon applying the brakes for wedging said blocks between the coupler and the end sill to take up the draw-bar slack.

3. The combination with a draw-bar, of a device for taking up the draw-bar slack and means operated by applying the brakes for actuating said device.

4. The combination with a car coupler, of cooperating wedge blocks interposed between the coupler and the end sill of the car and a lever mechanism operated upon applying the brakes for actuating said wedge blocks to take up the draw-bar slack.

In testimony whereof I hereunto set my hand.

PATRICK H. DONOVAN.
